E. L. DAHLQUIST

SPRING COMPRESSOR

Filed April 9, 1923

Inventor
Ernest L. Dahlquist.

By *Lancaster and Allwine*
Attorneys

UNITED STATES PATENT OFFICE.

ERNEST L. DAHLQUIST, OF AUBURN, IOWA.

SPRING COMPRESSOR.

Application filed April 9, 1923. Serial No. 630,987.

To all whom it may concern:

Be it known that I, ERNEST L. DAHLQUIST, a citizen of the United States, residing at Auburn, in the county of Sac and State of Iowa, have invented certain new and useful Improvements in Spring Compressors, of which the following is a specification.

This invention relates to tools, and is particularly well adapted for lifting and compressing the springs of the inlet and exhaust valves of an internal combustion engine to allow removal of the valves and stems.

15 The primary object of this invention is the provision of a valve spring compressing tool which will automatically lock when the spring has been sufficiently compressed and may be unlocked and opened by a very 20 simple movement and with a minimum amount of force.

A further object of this invention is to provide an improved valve spring compressing tool of few parts, eliminating the 25 complicated locking means yet producing a highly efficient tool, easy to operate and not susceptible of getting out of order.

A still further object of this invention is the provision of a tool that is strong, durable, and can undergo the rough usage, yet 30 is extremely light and cheap to make.

Other objects of the invention will appear in the following detailed description taken in connection with the accompanying drawing, forming a part of this specification, and in which drawing:

Figure 1 is a side elevation of the improved valve spring compressing tool showing the same in operative relation to a valve 40 spring before being compressed, a fragment of an internal combustion engine being shown.

Figure 2 is an end view of the tool in operation on a valve spring with the tool in a closed position and the spring compressed.

Figure 3 is a vertical central section through a portion of the tool.

Figure 4 is a cross section taken on the 50 line 4—4 of Figure 3, looking in the direction of the arrows.

Figure 5 is a perspective detail view of the spring engaging jaws of one of the shanks of the tool.

55 Figure 6 is a perspective detail view of

the spring engaging jaws of the other shank of the tool.

Referring to the drawings in detail, wherein similar reference characters designate corresponding parts throughout the several views, the letter A indicates the internal combustion engine of the ordinary or any preferred type and B the valve; C is the supporting or main shank member of the improved tool; D, the co-acting shank 65 and E the operating lever, whereby the tool is closed and locked or opened.

The valve B includes the valve stem 7, which is normally held in a lowered position for holding the valve on its seat by 70 the compression spring 8, which is coiled around stem 7. The cup shaped spring seat 9, provided loosely on stem 7, is held against displacement by any preferred means such as a pin or the like. Valve stem 75 7 is raised in the well known manner by the push rod 10 having the adjusting nuts 11 and 12 arranged on its upper end for the provision of clearance.

Referring now to the main shank member 80 C, same may be formed of metal, preferably U-shaped in cross section, having one end bifurcated to form fingers 13 and 14 adapted to engage the work, while the opposite end forms a convenient grip or handle 15. A 85 pair of upstanding lugs 16 and 17 carrying a transverse pin 18 pivotally support co-acting shank D which also carries a pair of engaging members 19 and 20 at its end adjacent the bifurcated end of shank C. These 90 fingers are rigidly mounted on shank D by rivets or analogous means 21 and have their engaging lugs 22 and 23 disposed on a higher plane than the shank D for the purpose of including a large number of spring 95 coils when in operation.

Concerning the operating lever E, such is also preferably made of metal or strong material and is substantially U-shaped with an elongated portion to form ears 24 and 25 100 by means of which it is pivotally mounted on shank C by a pintle 26. Transverse pins 27 may have an anti-friction roller 28 mounted thereon to slide along under surface of shank D when the device is operating. Stop pins 29 also carried by ears 24 and 25 serve as a limiting element to lock 105 and support lever E when in a completely opened or closed position, as shown in Figures 1 and 3.

It is to be particularly noticed that the relative distance of pins 26 and 27 and 29 away from the pivotal point 18 is of the greatest importance. In the operation and during the closing movement, pin 27 reaches or passes dead center and attains a position back of pin 26 while pin 29 is still further back of 27 and owing to the expanding tendency of the work 8 shank D is forced open at its engaging end and consequently closed as in a direction toward shank C at its opposite end which causes pin 29 to function as a stop or locking member for the jaws of the tool. The dotted position in Figure 1 shows the tool closed or locked.

Changes in details may be made, without departing from the spirit or scope of my invention; but,

I claim:

1. A spring compressor comprising in combination a supporting shank substantially U-shaped in cross section, a pair of upstanding ears carried thereby, a co-acting shank pivotally disposed between said ears of the supporting shank, spring engaging jaws carried on the adjacent ends of the shanks, and an actuating and a locking means including a lever straddling the shanks and having side arms pivotally mounted on the supporting shank, a roller rotatably mounted between said arms and positioned between the shanks and engaging the inner face of the second mentioned shank, and a pin carried by said side arms beneath said roller for engaging the supporting shank and limiting swinging movement of the lever.
2. In a spring compressor, the combination of a pair of co-acting engaging shanks disposed in pivotal relation, an operating and locking means comprising a lever having a forked end portion straddling the shanks and having its arms pivotally connected to one of said shanks, a guide carried by the arms and extending between the shanks to engage the inner face of one shank, and a locking pin carried by the arms beneath the guide and adapted to engage the inner face of the other shank and limit movement of the lever.

3. In a spring compressor, the combination of a pair of coacting shanks disposed in pivoted relation to each other, an operating and locking means comprising a lever with projecting sides extended at one end to straddle both shanks and pivotally carried by one of them, a transverse bearing roller and stop pin carried intermediate the coacting shanks, the stop pin being so situated between the pivotal point and said bearing roller that the expanding tendency of the work forces said operating lever into a locked position.

4. In a spring compressor, a pair of shanks pivotally connected at a point intermediate their lengths to provide forwardly and rearwardly extending portions, one of said shanks having its forwardly extending portion provided with means for engaging and supporting a spring supporting cup, arms carried by the forwardly extending portion of the second shank and curved outwardly to extend upon opposite sides of a spring, lugs extending upwardly from the end portions of said arms and having in-turned end portions for engaging convolutions of a spring at opposite sides of the spring, and actuating means cooperating with the rearwardly extending portions of said shanks.

5. In a spring compressor, a pair of shanks movable towards and away from each other, spring cup engaging means carried by one shank, arms carried by the other shank and shaped to extend in straddling relation to a spring, and lugs extending upwardly from said arms and having inwardly extending portions for engaging convolutions of the spring, at opposite sides of the spring.

6. A spring compressor including members movable towards and away from each other, spring cup engaging means carried by one of said members, and arms carried by the other member for straddling a spring and having lugs extending inwardly of the arms for engaging convolutions of the spring at opposite sides of the spring.

ERNEST L. DAHLQUIST.
